METHOD AND APPARATUS FOR MAKING
MANIFOLD FORMSFred B. Cole, Norwalk, Ohio, assignor to The
Rotary Printing Company, Norwalk, Ohio, a
corporation of Ohio

Application October 10, 1930. Serial No. 487,799

7 Claims. (Cl. 270—41)

This invention relates to apparatus, which is used for the manufacture of manifold forms. One form of such apparatus embodies a cylindrical member, such as a length of rigid pipe as 5 a guide over which the paper web passes. The guide is placed between the roll and the fingers which engage the longitudinally extending weakening lines, and press there-against to effect a longitudinal folding of the paper. It has been 10 found however, that the paper has a tendency to shift laterally along the guide, thus causing the weakening lines to get out of registration with the finger.

To remedy this difficulty, the practice has been 15 to stop the machine, to remove the guide, and to bend it slightly in one direction or the other, in order to compensate for the degree of side- wise movement which the paper has taken. After the adjustment has been made, the guide is put 20 back into place and the machine is again started. If the proper adjustment has not been made, it is necessary to repeat the operation, until the proper degree of curvature is obtained.

This procedure is objectionable, as it necessi- 25 tates considerable loss of time, and there is no accurate manner of determining the proper ex- tent or direction in which the guide should be bent. Furthermore, it is objectionable as an ad- justment may have to be made many times while 30 a single roll is being unwound, for the paper stretches and is apt to shift laterally at frequent intervals.

The principal object of the present invention therefore, is to provide a device whereby the cur- 35 vature of the guide may be accurately and quickly controlled without stopping the machine. In this connection, my invention contemplates the provision of a device which has few working parts, and which may be as readily adjusted in an ex- 40 ditious manner while the paper is in motion.

In the drawing, Fig. 1 is a diagrammatic view 45 illustrating a method of making manifold forms; Fig. 2 is a plan view of a portion of the machine embodying my invention, and Fig. 3 is a section taken on the line 3—3 in Fig. 2.

Referring now to Fig. 1, 10 indicates a roll of paper which is used for making manifold forms. The web of paper passes over a guide member 11, and thence downwardly where it is engaged by 50 fingers 12, which act upon the longitudinal weakening lines 13. After the paper is folded longitudinally, it is caused to pass through guide boxes 14, and 15, between which the transfer strips 16 are introduced into the folded forms. This 55 method of making manifold forms is illustrated,

described, and claimed in detail in Patent No. 1,753,764 issued to Louis J. Willard on April 8, 1930.

The present invention is concerned with a method of manipulating the paper while it is in motion so as to maintain the weakening lines in contact with the fingers, and thereby to insure accurate holding of the web longitudinally. I carry out this method by making the guide member 11 flexible, relatively movable with reference 60 to itself and by providing means for effecting such relative motion while the web is passing thereover. The preferred manner for obtaining such result is to utilize a flexible member, such as a strip of garden hose of the desired length. 65 This provides, not only the desired flexibility, but also satisfactory means for exerting friction upon the paper.

My invention includes means for moving one portion of the flexible guide member with refer- 70 ence to another portion thereof and to this end, I utilize a relatively stationary member 20, which is disposed beneath the flexible member. Upon the stationary member, I mount supporting de- vices 21 which are adapted for slidable and piv- 75 otal movement and are also adapted to be locked in any desired position by means of a set screw 22. One end of each member 21 is provided with a cup-shaped jaw 23 into which the flexible mem- 80 ber 11 extends, while the opposite end is provided with a handle 24 for enabling the proper degree 85 of adjustment to be made. By utilizing a plu- rality of independent adjusting members, I am able to shift any part of the flexible member back- 90 wards or forwards with reference to the paper web, and thereby selectively to control the ten- 95 sion on each edge of the paper. Thus, any ten- dency which the paper may have to shift laterally can be quickly overcome merely by oscillating the members 21 about the axis of the member 20. 95

I have found that by means of my invention, the lateral shifting of the paper web may be accurately controlled, and that the degree to which the flexible member must be bent can be quickly determined without requiring the machine 100 to be stopped. Thus, the longitudinal weaken- ing lines are maintained in contact with the fin- gers that control the folding operation, and the manufacture of manifold forms is greatly facili- 105 tated.

I claim:

1. A guiding member for a manifold form ma- 110 chine, comprising a flexible member and means for supporting the same, said means being adapt- ed to shift any portion of the member with refer-

ence to the remaining portions thereof, whereby the tension of the paper passing over the guiding member may be selectively controlled.

2. A guiding member for a manifold form machine, comprising in combination, a flexible member, a rigid member, a plurality of arms slidably and pivotally mounted on the rigid member, said arms being in operative engagement with the flexible member, whereby any part of the member 5 may be selectively bent with reference to another part thereof.

3. A guiding member for a manifold form machine comprising, a flexible member extending transversely of the form and having a surface 15 over which the form moves, and means for independently adjusting the contact surface of the member longitudinally of the form at any point transversely thereof.

4. A web guiding device comprising a flexible member positioned normally in the plane of the 20

web and normal to the direction of travel of the web, and means for shifting any portion of the member in either direction from said normal.

5. A web guiding device comprising a flexible member, a stationary member, and means for moving any portion of the flexible member in an arc about the stationary member. 80

6. A method of folding a web longitudinally comprising feeding the web over a guide and through folding fingers and selectively moving one part of the guide with reference to any other part of it while the web is in motion so as to counteract the tendency of the web to shift out of alignment with the fingers. 85

7. In an apparatus for making manifold forms, 90 the combination of a flexible web guide, and means for shifting any portion of the guide in an arc with reference to any other portion thereof, while the web is moving over the guide.
